US00D722196S

(12) **United States Design Patent**
Tucker et al.(10) **Patent No.:** US D722,196 S
(45) **Date of Patent:** ** Feb. 3, 2015(54) **ELECTRONIC SMOKING ARTICLE**(71) Applicant: **Altria Client Services Inc.**, Richmond, VA (US)(72) Inventors: **Christopher S Tucker**, Midlothian, VA (US); **Geoffrey Brandon Jordan**, Midlothian, VA (US); **Barry S Smith**, Hopewell, VA (US); **Ali A Rostami**, Glen Allen, VA (US)(73) Assignee: **Altria Client Services Inc.**, Richmond, VA (US)(***) Term: **14 Years**(21) Appl. No.: **29/469,741**(22) Filed: **Oct. 14, 2013****Related U.S. Application Data**

(62) Division of application No. 29/443,134, filed on Jan. 14, 2013, now Pat. No. Des. 691,765.

(51) **LOC (10) Cl.** ..... **27-01**(52) **U.S. Cl.**USPC ..... **D27/101**(58) **Field of Classification Search**

USPC D27/103-105, 108, 125, 172, 174-176, D27/183, 186-192, 194, 100, 101, 170, D27/163-165, 184, 185; D34/2; 206/242-276; D3/11, 215, 220, D3/226-230, 265, 266; 4/258, 259, 267, 4/271, 283; 131/270-273, 329, 330, 194, 131/189, 347, 360-365; D24/110, 113, D19/77, 81, 84; D28/73-77, 83, 85

Primary Examiner — Susan Bennett Hattan*Assistant Examiner* — Janice Hallmark(74) *Attorney, Agent, or Firm* — Harness, Dickey & Pierce, P.L.C.**CLAIM**

The ornamental design for an electronic smoking article, as shown and described.

DESCRIPTION

FIG. 1 is a perspective view of an electronic smoking article showing our new design.

FIG. 2 is side elevational view thereof, the other side being a mirror image; and,

FIG. 3 is an end elevational view thereof.

The broken line showing illustrates portions of the electronic smoking article which form no part of the claimed design.
